Letters Patent No. 2247 Dated Jan 30 1866

Ante-dated Dec 24 1865

Design for a Cook Stove

The schedule referred to in these Letters Patent and making part of the same

To all whom it may concern:

Be it known that I, Samuel H. Gibbs, of Albany, County of Albany, State of New York, have invented or produced a new and original design for a cook stove, named the "Chieftain", and I do hereby declare the accompanying Drawing with the following explanation of the same to form a full, clear and exact description of the said Design.

The view in the accompanying drawing represents the Chieftain cook stove, in perspective, A being the top plate, B the side plate, C the bottom plate, D, the upper front plate, E, the lower front plate and G, the hearth plate.

The top plate A is plain, and edged with a plain moulding. The side plate B, has a plain bead at each vertical edge and an ornamental moulding at the lower edge, and has a large window and two smaller doors, all of which have on their edges plain mouldings inclosing the ornamental work shown in the drawing.

The bottom plate C, is plain and edged with a plain moulding.

The upper front plate D, has two sliding doors having ornaments similar to those on the door of the side plate.

The lower front plate E, is plain with the exception of the ornamental moulding at the lower edge, which is similar to that at the lower edge of the side plates. The hearth plate G, is plain and edged with a plain moulding.

2

DES. 2247

Claim The ornamental figures and forms, substantially as represented in and by the accompanying drawing, the whole forming an ornamental design for a cook stove.

Testimony whereof I have signed my name to this specification in the presence of five subscribing witnesses.
